ELECTRON TUBE APPARATUS

Robert L. Jepsen, Palo Alto, Frederick L. Salisbury, Redwood City, and Curtis E. Ward, Palo Alto, Calif., assignors to Varian Associates, San Carlos, Calif., a corporation of California

Filed Feb. 6, 1953, Ser. No. 335,438

13 Claims. (Cl. 315—5.19)

This invention relates, generally, to electron tube apparatus and the invention has reference, more particularly, to novel apparatus of this type embodying component improvements applicable to velocity modulation tubes, traveling wave tubes and other tube types.

Ultra high frequency devices as of the velocity modulation type are being widely used as oscillators, amplifiers, modulators, etc., and heretofore have been delicate tubes assembled from a relatively large number of subassemblies having many small and delicate elements therein. The construction of these known devices has very often required the use of glass for the main body portion and has been such that careful handling and protection from even minor shock have been necessary when using these devices. These devices, because of their construction from multiple subassemblies and the number of elements in each device, have been larger and more cumbersome than necessary for efficient operation. Present day requirements, especially in the fields wherein the tubes are subjected to rough usage, demand electron devices which will be both compact and extremely rugged while still possessing improved operating characteristics over known devices.

Several difficulties encountered in discharge devices of the electron beam type, such as, for example, klystrons and traveling wave tubes, heretofore employed arise from an interaction between the electron beam and ions trapped along the path of the beam. These difficulties may include:

(1) Modulation of output power, frequency, and beam current at the frequency or frequencies of continuous ion oscillation. These frequencies are, typically, in the range of .1 megacycle per second to 10 megacycles per second.

(2) Modulation of output power, frequency, and beam current at both (a) ion oscillation frequencies (in the megacycles per second range) and (b) low frequencies (typically in the audio frequency range). The low frequency fluctuations are associated with the high frequency ion oscillations.

(3) Changes in output power, frequency, and beam current as the frequency of an applied modulating voltage is varied. These changes occur when the modulating frequency is near one of the frequencies of incipient ion oscillation. The changes may be abrupt or fluctuating.

As stated above, these difficulties arise from an interaction between the electron beam and ions trapped along the path of the beam. In reflex klystrons these ions are trapped in the re-entrant tube portion between the accelerator grid and the first resonator grid.

It is, therefore a principal object of this invention to provide a novel electron tube apparatus that is both compact and extremely rugged, while at the same time operably improved over existing electron devices of this type.

Another object of this invention is to provide an electron beam tube which is made up of a relatively few number of small subassemblies securely and compactly assembled together to form a small and rugged structure, each subassembly being made up of a relatively few elements, each rugged in its own right.

Another object of this invention is to provide an elec-

2

tron beam tube having a novel structure located in the electron beam path and associated with a portion of the tube which ordinarily traps positive ions therein, this novel structure substantially reducing the number of ions trapped therein.

5 A further object of this invention is to provide an electron beam tube wherein one of the walls forming the portion of the tube in the path of the electron beam which normally traps ions is a novel grid structure which permits the escape of the ions from the trap.

A further object of this invention is to provide a novel electron beam gun assembly which is structurally better than conventional gun assemblies in that it is more compact and rigid while at the same time provides the maximum electron emission with relatively lower heater current.

Other objects and advantages will become apparent from perusal of the following specification taken in connection with the accompanying drawings wherein one embodiment of the invention is depicted.

In the drawings,

FIG. 1 is a plan view of a reflex klystron embodying this invention,

FIG. 2 is a longitudinal sectional view of the reflex klystron shown in FIG. 1 showing a novel cathode gun assembly in plan view,

FIG. 3 is a transverse sectional view of the tube in a plane indicated by section line 3—3 in FIG. 1, the arrows indicating the direction in which the view is taken,

FIG. 4 is a section view of the novel cathode gun assembly shown in FIG. 2,

FIG. 5 is a transverse sectional view of the novel electron beam gun in a plane indicated by section line 5—5 in FIG. 4, the arrows indicating the direction in which the view is taken, and

FIG. 6 is a longitudinal part sectional view of the reflex klystron in a plane indicated by section line 6—6 in FIG. 1, the arrows indicating the direction in which the view is taken.

Referring to the drawings, the main body 1 of the reflex klystron is a unitary structure of metal such as steel comprising a block 2 having a rectangular shape and having oppositely extending end portions 3 and 4 cylindrical in shape protruding from the larger sides of the block 2. The body has a multi-diameter bore extending longitudinally through the body and axially aligned therein, the different diameter portions of the bore arranged in pyramidal step-like relationship. Located in the wall of one other side of the block is an elongated pan-shaped recess 5 having tapering side walls and a flat bottom surface in which is located an elongated opening 6 or iris extending into the smaller diameter portion of the bore of the body.

A unitary metallic header 7 serves the triple function of providing the mounting support for the accelerating grid 8 and the first resonator grid 9, providing boundary walls for the cavity resonator 10, and forming the re-entrant tube 11 of this reflex klystron. This header 7 is ring-shaped with a projecting annular portion 12 and a two-step axially aligned bore therein, this bore forming the re-entrant tube of this klystron. Fixedly mounted as by gold brazing on one side of this header 7 and axially aligned with the bore therethrough is a round honey-combed accelerating grid 8. Fixedly mounted as by gold brazing on the opposite side of the header 7 on the

65 projecting annular portion 12 is a round honey-combed copper resonator grid 9, the longitudinal thickness of this resonator grid being of the order of .04" thick, or approximately four times the thickness of the accelerating grid 8. This metallic header 7 and copper grids 8 and 9 form one subassembly, this subassembly being slipped into the portion of the body 1 having the small-

est diameter at a point adjacent to the iris 6 and secured therein as by silver brazing.

A second round honey-combed resonator grid 13 is mounted as by gold brazing on a cup-shaped metallic header 14 having an axially aligned bore therein. This second subassembly is placed within the smallest diameter portion of the bore of the body 1 adjacent the iris 6, carefully spaced from the first resonator grid 9 and fixedly secured therein as by silver brazing. This header 14, besides serving as the mounting element for the second resonator grid 13, also serves as one of the walls forming the cavity resonator 10. Thus, the cavity resonator 10 is formed by the inside surface of the portion of the smallest diameter bore of the body 1 between the headers, one surface of the header 7 and the annular portion 12 thereof, the two resonator grids 9 and 13, and one surface of the header 14.

The third or reflector subassembly comprises a shallow cup-shaped metal, such as nickel, reflector 15 which may be spotwelded to the end flange of a conducting collar 16, this collar in turn encompassing one end of a hollow conducting post 17, the post being secured as by spotwelding within the collar 16. The reflector mounting post 17 is fixedly secured and sealed within the mounting cup 18 by a glass-to-metal type seal 19. A wire reflector lead or terminal 21 extends into the hollow reflector post 17, the end of the post being crimped around the lead, the junction being sealed and secured as by silver brazing. This reflector subassembly is then mounted within the reflector end of the unitary tube body 1, the outer flange 22 of the mounting cup 18 being fixedly secured within the largest diameter bore of the metal body 1 as by silver brazing. A small hole 23 in the reflector 15 permits evacuation of the space within the hollow reflector post 17 during evacuation of the tube.

The fourth or cathode subassembly is a novel cathode gun assembly which is extremely rugged and is more compact than heretofore existing gun assemblies. It should be noted that this novel cathode gun assembly is mounted entirely within the small metal body of the tube and thus reduces the length of the tube device by about one-fourth as compared with klystrons having the same size body 1 but utilizing conventional beam gun assemblies which protrude from the end of the body 1. This cathode gun assembly comprises a cathode button 46 as of nickel (see FIG. 4) having a slightly concave shape and an annular flange 47 encircling the periphery thereof. This cathode button is coated with a conventional electron emissive oxide substance and is mounted on a cathode mounting member 48 made of a strong but poor thermal conducting material such as a metal alloy. This member has a two-step hollow cylindrical-like shape closed at one end 49. The surface of the closed end preferably has the same concave curvature as the cathode button. The cathode button is mounted above this surface as by spotwelding the inside wall of the cathode button flange 47 to the outer upper wall of the mounting member 48. The heater wire 51 is sandwiched in the narrow space between the under surface of the cathode button 46 and the upper surface of the end 49 of the mounting member 48. The sandwiched heater wire 51 extends in a wavy or sinuous fashion to and fro in this small space, doubling back on itself to thereby provide a maximum length of wire under the cathode button as shown in FIG. 5. It should be understood that the heater wire could be wound in a flat spiral under the cathode button or could assume other configurations. The ends of the heater wire extend down through the mounting member through two openings in the closed end thereof. A disk-like heat reflector 52 as of nickel is spotwelded or otherwise secured on the under surface of the step in the member 48. This reflector 52 also has two openings therein to allow passage-through of the heater wire 51. This mounting member 48 is then secured within the cylindrical focussing ring 53 as by spotwelding the outer surface of the larger diameter portion

of the cylindrical mounting member 48 to the inside surface of the focussing ring 53. One end of the heater wire is preferably spotwelded to a nickel ribbon 54, the other end of the nickel ribbon being similarly spotwelded to the heat reflector 52. The inner open end of the cathode assembly supporting cup 55 is closed with a glass-to-metal seal through which five leads extend, three of these leads being combination electrode terminals and mounting wires and the remaining two being mounting wires. The cathode gun assembly is mounted on the latter two mounting wires 56 and 57 and one of the other wires 58, which is the common terminal for the getter, cathode and heater. A ribbon 59 as of nickel encircles the lower portion of the focussing ring 53 and the three wires 56, 57 and 58 and is secured to each as by spotwelding. The getter 61 is secured at one end to the common terminal lead 58 and at the other end to the getter terminal lead 62 as by spotwelding. The fifth terminal lead 63 is secured as by spotwelding to a ribbon 64 as of nickel which in turn is spotwelded to one of the ends of the heater wire 51. The flanged outer end of the cathode assembly supporting cup 55 is secured as by brazing in the larger diameter portion of the bore of the body 1 along with a shim 27 as of nickel, the cathode gun assembly extending into the bore. As compared with existing cathode gun assemblies, this novel assembly, in addition to decreasing the length of the reflex klystron, greatly reduces the longitudinal length of the focussing ring and the cathode mounting member 48 while at the same time provides a large amount of heater wire in close association with the cathode button. The cathode button is thus more uniformly and more intensely heated by the current in the heater wire. Because of the greatly decreased lengths of the focussing ring and cathode mounting members, the diameters of the cross sections of the focussing ring 53 and cathode mounting member 48 are greater than the length of these elements and these elements are thus far more rigid than heretofore possible. The possibility of vibration of the cathode button and heater wire assembly is therefore greatly reduced.

The fifth or output waveguide assembly comprises a hollow rectangular metallic waveguide window adapter 28. This adapter is flanged on one end and has four small shelf-like indentations 29 in the side thereof. A rectangular window cup 31 has a sheet of glass 32 sealed across the opening in the end thereof. The window cup 31 is set within the open end of the window adapter 28, resting on the shelf-like indentations 29, and is sealed therein as by silver brazing. This window assembly is then mounted on the surface of the tube body surrounding the iris 6, the flanged end of the window adapter 28 being secured as by copper-gold brazing to the body. A rectangular section of waveguide 33 made of suitable alloys or metal is secured as by copper-gold brazing to a waveguide flange 34, this flange 34 providing for connection to a standard output waveguide circuit. A pair of tube support brackets 35 and 36 are brazed at one end thereof to the flange 34, the brackets extending flush against the larger sides of the block 2 and being fastened thereto by means of screws 37. Mounted on the brackets is a terminal strip 38 of insulation material for use in terminating the reflector, cathode and heater leads. A metal tube 39 extends from the side of the klystron body and is secured therein as by brazing, this tube serving as the point of evacuation of the tube. After evacuation the end of the tube is crimped and sealed closed.

In operation of this device, a heater current is supplied to the heater wire 26 to produce a stream of electrons from the cathode button 25. The accelerating grid 8 is at a positive potential with respect to the cathode and the electrons are attracted to this region and accelerated, the electrons reaching a constant velocity in the re-entrant tube 11 formed by the header 7. The electrons pass through the gap between the two resonator grids 9 and 13 where the electrons are acted on by the electric field across the gap to velocity modulate these electrons. The nega-

tively charged reflector 15 repels the approaching electrons and turns them about, the electrons then passing through the resonator gap between the resonator grids in bunches and giving up high frequency energy to the field in the cavity resonator 10. The electrons thereafter are collected on the walls of the tube and the first resonator grid 9. The first resonator grid is made thick to thereby intercept a large number of electrons passing through on their return trip from the reflector to the cathode area and thus reduce the number of multiple transit electrons. The high frequency power produced in the cavity resonator passes through the iris 6 into the waveguide section and then through the glass seal to the output waveguide circuit.

In heretofore existing reflex klystrons, an ion trap is formed in the re-entrant tube by the accelerating grid and the first resonator grid. The positive ions, produced, for instance, by collision of the electrons and gas molecules, are collected in the re-entrant tube and perturb the electron beam, thus giving rise to the above noted difficulties. A novel structure is shown herein which greatly reduces the number of positive ions trapped within the re-entrant tube portion to thereby eliminate these difficulties and in addition spread the center of the beam. This novel structure comprises an accelerating grid 8 including an annular frame 41 (see FIG. 3) and a network of honey-combed vanes 42 as of copper supported by and extending within the frame 41. The interstices formed by the intersecting vanes 42 of the positively charged accelerator grid 8 provide a relatively intense electric field for coaxing with the beam. Located approximately in the center of the honey-combed vanes is an enlarged polygonal opening 43. This polygonal opening 43 in the positively charged accelerator grid permits the positive ions in the re-entrant tube to pass therefrom through the positive region of the accelerating grid to the negatively charged cathode area where they are collected on the various tube elements. Neither the size, nor the position, nor the shape of this opening 43 in the grid is absolutely critical for any particular embodiment, the only requirement being that the opening is about in the center of the grid and is of the proper size and shape to prevent trapping an excessive number of positive ions in the re-entrant tube portion. In the present embodiment of this invention an accelerating grid having an overall diameter of about .26" was employed. The inside diameter of the grid frame 41 was about .19" while there were approximately 190 holes in the honey-combed vanes. The larger opening in the center of the honey-combed vanes was approximately .05". The size, shape and/or position of the opening 43 will vary depending on each particular application of this invention. This special type of grid may be utilized wherever ion traps may occur in various types of electron discharge tubes other than this particular reflex klystron embodying the invention as, for example, in drift spaces in multi-cavity klystrons.

Since many changes could be made in the above construction of the novel electron tube apparatus and many apparently widely different embodiments of this invention could be made without departing from the scope thereof, it is intended that all matter contained in the above description or shown in the accompanying drawings shall be interpreted as illustrative and not in a limiting sense.

What is claimed is:

1. In an electron beam discharge device, a main body comprising a rectangular metallic block having oppositely extending cylindrical end portions protruding from two opposite sides of the rectangular block, the body having an axially aligned bore extending through the cylindrical end portions and the rectangular block, the body having a slit-like window opening on one other side of the rectangular block extending perpendicular to the axis of the bore, a metallic cylindrical header having an axially aligned bore therethrough defining a re-entrant tube with-

in the header, an accelerator grid fixedly mounted on this header at one end of the bore and a first resonator grid fixedly mounted on this header at the opposite end of the bore, the header and associated grids being mounted within the bore of the body adjacent the window opening, a second round metallic header having an axially aligned bore therethrough and a second resonator grid mounted thereon, the second header being mounted within the bore of the body adjacent to and on the opposite side of the window from the first header and so positioned as to provide a predetermined spacing between the first and second resonator grids, whereby the bore of the body, the surfaces of the two headers, and the two resonator grids form a resonator cavity within the body having the window in the side wall thereof.

2. An electron beam discharge device including a main body comprising a rectangular metallic block and oppositely extending cylindrical end portions protruding from two opposite sides of the rectangular block, the body having an axially aligned bore extending through the cylindrical end portions and the rectangular block, the body having a slit-like window opening in one side of the rectangular block extending perpendicular to the axis of the bore, a metallic cylindrical header having an axially aligned bore therethrough defining a drift space within the header and an accelerator grid and a first resonator grid fixedly mounted on the header at opposite ends of the bore therethrough, the header and associated grids being mounted within the bore of the body adjacent the window opening, a second round header having an axially aligned bore therethrough and a second resonator grid mounted thereon over this bore, the second header being mounted within the bore in the block of the body on the opposite side of the window from the first header with the second resonator grid closely adjacent the first resonator grid, a reflector assembly comprising a reflector mounted on a mounting post, the mounting post being fixedly mounted within the bore in the outer end of one of the cylindrical end portions of the body with the reflector extending into the bore of the body and closely spaced from the second resonator grid, a cathode gun assembly mounted within the bore of the body at the outer end of the other cylindrical end portion with the cathode gun extending inwardly into the bore of the body and closely spaced from the accelerator grid, and an output waveguide section mounted at one of its ends on the block portion of the body and encircling the iris window, the other end of the waveguide being closed by a glass-to-metal seal.

3. A cathode gun assembly comprising a cylindrical focussing ring, an electron emissive cathode and a heater wire mounted within the focussing ring, a cylindrical cathode assembly supporting member having open ends and a glass-to-metal seal across one of the open ends in the member, a plurality of mounting wires extending out from the supporting member and imbedded in the glass-to-metal seal, the wires engaging the outer surface of the focussing ring at spaced points around the ring, and a metallic ribbon encircling the focussing ring and the mounting leads and securely affixed thereto to thereby rigidly hold the focussing ring, cathode and heater wire in fixed position with respect to the supporting member.

4. A cathode gun assembly comprising an electron emissive concave disk-shaped cathode button having a flange around the peripheral edge thereof, a cylindrical cathode mounting member having a closed end with a concave surface, the cathode button being mounted over and spaced from the closed end of the mounting member with its flange engaging the outer surface of the cylindrical mounting member and being affixed thereto, a heater wire positioned between the cathode button and the closed end of the mounting member and arranged to occupy the major portion of the space therebetween, the ends of the heater wire extending through openings in the closed end of the mounting member, and a cylin-

cylindrical focussing ring, the cathode mounting member being fixedly secured within the focussing ring with its outer surface engaging the inner surface of the ring, the cathode button extending within the focussing ring.

5. In an electron beam discharge device having means for producing a beam of electrons, a hollow enclosure positioned in the path of the beam having open ends through which the beam enters and leaves the hollow enclosure, a first grid closing one end of said enclosure and a second grid mounted over the other open end of the enclosure, said second grid having a plurality of intersecting grid vanes therein forming a honey-comb configuration defining small interstices between the vanes and having an opening approximately in the center of the grid vane network having a diameter greater than three times that of the other interstices through which ions trapped in the hollow enclosure are drained in use.

6. In an electron beam discharge device having means for producing a beam of electrons, a re-entrant tube in the path of the electron beam comprising side walls and a pair of grids mounted on each end of the re-entrant tube transverse to the path of the beam, one of said grids being a honey-combed accelerator grid adjacent the cathode region of the device, said accelerator grid having a plurality of intersecting vanes therein defining small interstices therebetween providing a relatively intense electric field in use for coaxing with the beam and having an enlarged opening approximately in the center of the grid vane network greatly larger than any of the other interstices through which ions trapped in the re-entrant tube can be drained into the cathode region.

7. An electron discharge device comprising a main body having an axially aligned bore extending therethrough and having a slit-like window opening in the side thereof extending perpendicular to the axis of the bore, an annular metallic header including a hollow cylindrical re-entrant tube portion, the bore of said re-entrant tube being axially aligned in the bore of the main body, an accelerator grid mounted over one end of the re-entrant tube bore and a first resonator grid mounted over the other end of the re-entrant tube bore, the header and re-entrant tube portions and the associated grids being mounted within the bore of the body adjacent the window opening, a second metallic header having an axially aligned bore therethrough and a second resonator grid mounted over the bore thereof, the second header being mounted within the bore of the body adjacent to the window on the opposite side from the first header and so positioned as to provide a predetermined spacing between the first and second resonator grids whereby the bore of the body, the surfaces of the two headers and the two resonator grids forming a resonator cavity within the body having the window in the side wall thereof.

8. An electron beam discharge device including a main body having an axially aligned bore extending therethrough, the body having a slit-like window opening in the side extending perpendicular to the axis of the bore, an annular metallic header including a hollow cylindrical re-entrant tube portion, the bore of said re-entrant tube being axially aligned in the bore of the main body, an accelerator grid mounted over one end of the re-entrant tube bore and a first resonator grid mounted over the other end of the re-entrant tube bore, the header and re-entrant tube portions and the associated grids being mounted within the bore of the body adjacent the window opening, a second metallic header having an axially aligned bore therethrough and a second resonator grid mounted over the bore thereof, the second header being mounted within the bore of the body adjacent to the window on the opposite side from the first header and so positioned as to provide a predetermined spacing between the first and second resonator grids, a reflector assembly comprising a reflector mounted on a mounting post, the mounting post being fixedly mounted within the bore in

one outer end of the body with the reflector extending into the bore of the body and closely spaced from the second resonator grid, a cathode gun assembly mounted within the bore of the body at the other outer end with the cathode gun extending inwardly into the bore of the body and closely spaced from the accelerator grid and a wave energy permeable material covering the iris window.

5. A reflex klystron including a cathode adapted to produce a beam of electrons, a re-entrant tube member, a cavity resonator, a reflector electrode, and an accelerator grid covering the open end of the re-entrant tube member near the cathode region, the grid being a honeycombed accelerator grid having a plurality of intersecting grid vanes therein defining small interstices therebetween and having an enlarged opening approximately in the center of the grid vane network larger than the other interstices through which ions in the re-entrant tube member may be drained into the cathode region.

10. A reflex klystron comprising cathode means adapted to produce a beam of electrons directed along a path in the klystron, a reflector electrode positioned in the path adapted to repel the electrons, a hollow member forming a re-entrant tube positioned in the beam path between the cathode means and the reflector, a cavity resonator member positioned in the beam path between the re-entrant tube member and the reflector including a resonator grid mounted on the reflector end of the hollow re-entrant tube member and a honeycombed accelerator grid mounted on the cathode end of the hollow re-entrant tube member having a plurality of intersecting vanes therein defining small interstices therebetween and having an enlarged opening approximately in the center of the grid vane network through which ions that may normally be trapped between the accelerator grid and the resonator grid in the re-entrant tube member may be drained to the cathode region.

15. An electron beam discharge device including a main body comprising a metallic block having oppositely extending cylindrical end portions and an axially aligned bore extending through the cylindrical end portions and the block, a metallic cylindrical header mounted in the device having an axially aligned bore therethrough defining a re-entrant tube within the header, an accelerator grid fixedly mounted on this header at one end of the bore and a first resonator grid fixedly mounted on this header at the opposite end of the bore, said accelerator grid being a honeycombed grid having a plurality of intersecting grid vanes therein defining small interstices therebetween and having an enlarged opening approximately in the center of the grid vane network larger than the other interstices through which ions in the re-entrant tube member may be drained into the cathode region, and a cathode gun assembly mounted in one cylindrical end portion adjacent said accelerator grid comprising a cylindrical focusing ring, an electron emissive cathode and a heater wire mounted within the focusing ring, a cylindrical cathode assembly supporting member having open ends and an insulator seal across one of the open ends in the member, a plurality of mounting wires extending out from the supporting member and imbedded in the insulator seal, the wires engaging the outer surface of the focusing ring at spaced points around the ring, and a metallic ribbon encircling the focusing ring and the mounting leads and securely affixed thereto to thereby rigidly hold the focusing ring, cathode and heater wire in fixed position with respect to the supporting member.

20. An electron discharge device comprising a main body having an axially aligned bore extending therethrough, an annular metallic header including a hollow cylindrical re-entrant tube portion mounted in said body, the bore of said re-entrant tube being axially aligned in the bore of the main body, an accelerator grid mounted over one end of the re-entrant tube bore and a first resonator grid mounted over the other end of the re-entrant

tube bore, and a cathode structure mounted in the bore of the body adjacent said accelerator grid comprising a cylindrical focusing ring, an electron emissive cathode and a heater wire mounted within the focusing ring, a cylindrical cathode assembly supporting member having open ends and an insulator vacuum seal across one of the open ends in the member, a plurality of mounting wires extending out from the supporting member and imbedded in the vacuum seal, the wires engaging the outer surface of the focusing ring at spaced points around the ring, and a metallic ribbon encircling the focusing ring and the mounting leads and securely affixed thereto to thereby rigidly hold the focusing ring, cathode and heater wire in fixed position with respect to the supporting member.

13. An electron beam discharge device comprising a cathode gun assembly for producing a beam of electrons including a cylindrical focusing ring, an electron emissive cathode and a heater wire mounted within the focusing ring, a cylindrical cathode assembly supporting member having open ends and an insulator vacuum seal across one of the open ends in the member, a plurality of mounting wires extending out from the supporting member and imbedded in the vacuum seal, the wires engaging the outer

5 surface of the focusing ring at spaced points around the ring, and a metallic ribbon encircling the focusing ring and the mounting leads and securely affixed thereto to thereby rigidly hold the focusing ring, cathode and heater wire in fixed position with respect to the supporting member, a hollow enclosure positioned in the path of the beam having open ends through which the beam enters and leaves the hollow enclosure, a first grid closing one end of said enclosure and a second grid mounted over the other open end of the enclosure adjacent the cathode gun assembly, said second grid having a plurality of intersecting grid vanes therein forming a honeycomb configuration defining small interstices between the vanes and having an opening approximately in the center of the grid vane network having a diameter greater than three times that of the other interstices through which ions trapped in the hollow enclosure are drained into the cathode region.
